RUFFLER

Herbert H. Russell, New Haven, Conn., assignor
to The Greist Manufacturing Company, New
Haven, Conn., a corporation of Connecticut

Application August 27, 1952, Serial No. 306,530

2 Claims. (Cl. 112—135)

1

This invention relates to sewing machine attachments and more particularly to an attachment for making ruffles or gathers, which attachment can be attached to the usual household sewing machine.

In devices of this kind it is usual to provide a frame adapted to be attached to the presser bar of the sewing machine upon removal of the presser foot, and this is true of the present attachment. Upon this frame is pivoted a pendulum lever which is connected at its lower end to a carrier to which the ruffling blade is attached. The pendulum lever is oscillated by the oscillations of a fork arm pivotally carried by the frame, the fork arm being bifurcated at its forward end to embrace the needle screw of the needle bar of the sewing machine to which the device is attached, so that upon reciprocation of the needle bar gathers or ruffles will be made in the material and stitches will be effected through these gathers or ruffles.

To this end a pawl member is carried by the fork arm, which pawl member is provided with a tooth to engage a shoulder provided on the pendulum lever to move the latter in one direction, and a screw or "kicker" is mounted on the fork arm to engage a part of the pendulum lever and move it in the other direction. It is desirable to provide means for varying the spacing apart of the ruffles or gathers so as to vary the number of machine stitches between adjacent ruffles, and to this end a ratchet wheel is rotatably mounted on the frame to be engaged by the pawl on the fork arm.

This ratchet wheel is provided with deep and shallow notches, the arrangement being such that when the pawl member engages the shallow notches, it will not be permitted to engage the shoulder on the pendulum lever and, therefore, will not actuate the latter. When, however, the pawl member is engaged in one of the deep notches of the ratchet wheel, it will be permitted to engage this shoulder on the pendulum lever and, therefore, effect a movement of the ruffling blade.

In order to vary the spacing of the ruffles, interchangeable ratchet wheels are provided having different arrangements thereon of the deep notches so that a ruffle can be made, for example, upon every third stitch of the machine, every fourth stitch, every sixth stitch, or any other desired arrangement.

As shown, the ratchet wheel is provided with twelve notches and, therefore, any arrangement can be provided in which the ruffle may be made

2

upon any stitch of which twelve is a multiple. This, of course, can be varied if desired, and the ratchet wheels provided with a different number of teeth.

As it is necessary to substitute one ratchet wheel for another when providing for a different spacing of the ruffles, it is desirable to provide a simple and easily manipulatable mechanism for securing the ratchet wheels in place so that they may be readily removed and replaced. The present invention relates particularly to a new method of securing the ratchet wheels in place and the associated mechanism.

One object of the present invention is to provide a new and improved sewing machine attachment for making ruffles or gathers.

A further object of the invention is to provide a new and improved sewing machine attachment having interchangeable ratchet wheels for varying the spacing of the ruffles made by the attachment and having convenient and easily operated mechanism for removably securing one of the ratchet wheels in place.

Another object of the invention is to provide a ruffler attachment for sewing machines of the character described wherein the means for securing one of the ratchet wheels in place is a resilient or spring member releasably secured in operative position but readily moved to an inoperative position to permit the removal of the ratchet wheel from the machine.

Still another object of the invention is to provide a ruffler attachment for sewing machines of the character described in which the member for securing the ratchet wheel in place is provided with a holding pawl to prevent reverse movement of the ratchet wheel.

To these and other ends the invention consists in the novel features and combinations of parts to be hereinafter described and claimed.

In the accompanying drawing:

Fig. 1 is a side elevational view of a ruffler attachment embodying my invention;

Fig. 2 is a fragmentary view similar to Fig. 1 showing the securing member for the ratchet wheel in another position;

Fig. 3 is a detail view of one of the ratchet wheels employed with the ruffler attachment; and

Fig. 4 is a side elevational view of the ratchet wheel securing member.

To illustrate a preferred embodiment of my invention I have shown a ruffler attachment for sewing machines including a frame which comprises an upwardly inclined frame member 10

to the forward end of which is secured an adaptor 11 for attachment to the presser bar of the sewing machine. Pivotally mounted at 12 upon the frame member 10 is the usual fork arm 13 having a bifurcated front end 14 adapted to be connected to the presser bar of the sewing machine in the usual manner.

Also pivoted at 12 to the frame member 10 is a pendulum lever 15, this lever having at its upper end a shoulder 16 adapted to be engaged by a pawl member 17 carried by a pawl carrier 18 mounted on the fork arm 13 in the usual manner.

To the lower end of the pendulum lever 15 is pivoted a carrier 20 for the ruffling blade 21. It will be obvious that as the fork arm is reciprocated, the pawl 17 will strike the shoulder 16 and thus move the pendulum lever in one direction to effect the making of a ruffle. To move the pendulum lever in the other direction the latter is provided with a shoulder 22 adapted to be engaged by a screw 24 adjustably mounted on the fork arm so that by adjustment of the screw the throw of the ruffling blade is adjusted and thus the width of the ruffle is varied. It will be understood that the parts heretofore described are old in the art and are not a part of the present invention.

It will be seen that if the pawl 17 strikes the shoulder 16 at each reciprocation of the fork arm 13, a ruffle will be made at each reciprocation of the needle bar or at each stitch of the sewing machine. In order to vary the spacing between the ruffles, ratchet wheels are provided which control the engagement of the pawl with the shoulder 16 of the pendulum lever. As shown in Figs. 1 and 2, a ratchet wheel 25 is rotatably mounted upon the pivot 12, this ratchet wheel being provided with shallow teeth 26 and deep teeth or notches 27. As shown there are five of the shallow teeth or notches between the deep notches 27 of which two are provided. The pawl member 17 is of sufficient width to engage this ratchet wheel as well as to engage the shoulder 16 of the pendulum lever, and the ratchet wheel is so constructed that when the pawl 17 is in engagement with one of the shallow notches or teeth 26, it will be held out of engagement with the shoulder 16. When, however, the pawl lies in one of the deep notches 27, it will be permitted to engage the shoulder 16.

As the ratchet wheel will be rotated through one tooth space at each oscillation of the fork arm, it will be seen that when the ratchet wheel 25 is used, there will be a stroke of the ruffling blade at every sixth stitch or twice during a complete rotation of the ratchet wheel which contains twelve teeth in all. In order, however, to vary the spacing of the ruffles, ratchet wheels having a different arrangement of teeth may be provided. For instance, as shown in Fig. 3, a ratchet wheel 28 may be employed which is provided with four of the deep teeth or notches 29 and between these notches are two shallow teeth or notches 30 so that if this ratchet wheel is employed, a three-stitch ruffle results.

It is, therefore, desirable to provide a convenient and readily manipulatable means for securing the various ratchet wheels in place so that they may be removed and replaced easily. To this end a retaining member 31 is pivoted at 32 to the inclined frame member 10. This member 31 is made of spring steel or similar resilient material,

it being quite thin, as shown in side view in Fig. 4. The body portion of the retaining member is slightly offset from the lower or pivoted end as shown at 33 so as to clear the ratchet wheel. The retaining member is also provided with an opening 34 designed to receive the pivot pin 12 which is slightly longer than necessary to accommodate the ratchet wheel 25.

The member 31 is so tensioned that it is normally urged toward the frame member 10 so that when it is moved about its pivot 32 into the position shown in Fig. 1 in which the opening 34 will register with the pivot pin 12, it will snap into position against the ratchet wheel and hold the latter in place with the pin 12 received in the opening 34. The resilience of the retaining member 31, however, allows the operator to engage the curved end 35 with his finger or thumb and move the retaining member outwardly so as to disengage it from the pin 12 and permit it to be moved to the position shown in Fig. 2. In this position the ratchet wheel may be removed and replaced by another of different formation.

A holding pawl member 36 is carried by the retaining member and may be conveniently provided by striking inwardly a portion of the metal of this member. This holding pawl is provided at a position to engage the teeth of the ratchet wheel, as shown in Fig. 1, and prevent reverse movement of the wheel when the fork arm is moved downwardly by the needle bar. Thus the ratchet bar will be positively actuated through a distance of one tooth space by each reciprocation of the fork arm.

While I have shown and described a preferred embodiment of my invention, it will be understood that it is not to be limited to all of the details shown, but is capable of modification and variation within the spirit of the invention and within the scope of the claims.

What I claim is:

1. A sewing machine attachment comprising a frame, a fork arm pivoted thereon, a ratchet wheel rotatably mounted on the frame for operation by the fork arm, and means for removably holding said ratchet wheel in place, comprising a retaining member pivoted on the frame to be moved to and from a position overlying the ratchet wheel, and said retaining member having a pawl thereon to engage the teeth of the ratchet wheel and prevent reverse rotation thereof.

2. A sewing machine attachment comprising a frame, a fork arm pivoted thereon, a ratchet wheel rotatably mounted on the frame for operation by the fork arm, and means for removably holding said ratchet wheel in place, comprising a retaining member pivoted on the frame to be moved to and from a position overlying the ratchet wheel, and said retaining member having a portion struck from the body thereof to form a holding pawl engaging the teeth of the ratchet wheel.

HERBERT H. RUSSELL.
